(57) **CLAIM**

The ornamental design for a blade iron, as shown and
described.

DESCRIPTION

FIG. 1 is a perspective view from below of a blade iron in
accordance with my design;

FIG. 2 is an enlarged perspective view from above of the
blade iron in accordance with my design;

FIG. 3 is an enlarged right side elevation view of the blade
iron in accordance with my design;

FIG. 4 is an enlarged left side elevation view of the blade
iron in accordance with my design;

FIG. 5 is an enlarged top plan view of the blade iron in
accordance with my design;

FIG. 6 is an enlarged bottom plan view of the blade iron in
accordance with my design;

FIG. 7 is an enlarged inverted front elevation view of the
blade iron in accordance with my design; and,

FIG. 8 is an enlarged inverted back elevation view of the
blade iron in accordance with my design.

The broken line showing of the ceiling fan canopy, motor
housing, support pole, and blades in FIG. 1 and blade iron
attachment member in FIGS. 2-6 and 8 is included for the
purpose of illustrating environmental structure and forms no
part of the claimed design.
